UNITED STATES PATENT OFFICE.

WILLIAM E. WILSON, OF MASON CITY, IOWA, AND HENRY G. LYKKEN, OF MINNEAPOLIS, MINNESOTA.

TUNNEL KILN.

Application filed June 14, 1924. Serial No. 720,115.

The present invention relates to kilns of the tunnel type through which wares may be moved or conveyed in stacks or decks, as upon cars.

5 Where, in kilns of this type, the sectional area of the cooling section is approximately the same as that of the rest of the kiln, the cooling of the ware is accomplished by radiation of the walls which in turn may be cooled

10 by air circulating in the walls, if made hollow for that purpose, or outside the walls, or air cooled pipes may be used in the cooling section of the kiln to remove the heat radiated from the wares, or air may be circulated through the wares in the cooling tunnel proper. These have the disadvantage of requiring long cooling sections, with the attendant cost of installation and maintenance, and the difficulty of controlling the

15 air in the case of cooling with air circulation in the tunnel sections, and not having the advantages that may be had by convection of the cooling medium.

In kilns having drying and heating sections where the heating gases are circulated through the ware in the passages of the sections the control of the circulation and the progression of the heating gases through the tunnel have not, heretofore, been satisfactorily controlled and regulated so as to obtain a uniform and efficient circulation and distribution of the heating medium as well as a uniform withdrawal of the medium at the entry end of the kiln.

35 Among the objects of our invention are to provide the cooling section of the kiln with space additional to that simply required for the passage of the ware, preferably above the ware passage and preferably at least equal in height to or of greater height than the ware passage in added extension thereto, depending upon the height, the cooling medium, such as air, should rise above the ware, it being understood, however, that such space might be vertically beneath such passage, if desired, as well as above such passage whereby the convection currents may rise or descend vertically in the space for the proper convection action and return into the ware

40 at successive places or parts for progression through the ware to effect the cooling action, to obtain proper convection action and for giving space or place to the relatively cooler

medium which may, in turn, progressively cool the ware; to provide a novel construction for giving free play to the convection currents of the medium used for cooling the ware, which free play and action could not be possible in a restricted tunnel or ware passage; to provide a construction where rapid and efficient cooling may be obtained with a shorter cooling section than heretofore and without the danger of the check-
ing of the ware; to provide for the admitting of the cool or cold medium at the bottom or near the bottom and at or near an end of the cooling section and permitting the rising of such medium through the ware, as it is heated by the ware and into the space provided vertically above or below the ware; to provide for an elevated exit of the heated medium in the space above the ware; to provide for cooling the ware progressively whereby the cold medium is partially heated in the relatively cool part of the section and rises in temperature or takes up heat in stages, the medium rising above the ware and being cooler and heavier than the medium further in the section, then passing downwardly through a further or forward part of the ware to displace the hotter medium rising to the space above, and so on to the end of the section when the hottest medium is exhausted at the upper part of such space, the hot air being then used for heating or drying or both in the heating and drying sections of the kiln, if desired; to provide for controlling of the cold medium supplied or admitted to the section; to provide a sealing passage between the firing or burning section of the kiln and the cooling section thereof; to provide for preferably a single hot medium duct preferably extending the length of the drying and pre-heating sections of the kiln; to provide for lead bleeders to such duct from the cross ducts on the car decks; to provide for multiple controlled exhaust ports; to provide means such as an exhaust fan for exhausting the gases or the other medium along the car decks and from the duct; to preferably provide the bleeders at intervals, as at every second car or the like; to provide means for controlling and regulating the section or withdrawal at each bleeder duct, such as by the use of dampers or valves and the like; to provide

for forcing the hot gases, near the roof of the kiln, to descend into the ware by the drawing off of the cooled gases at the bottom of the cars; to discharge hot medium 5 into the upper part of the kiln partly into either the drying and heating sections or both; to uniformly and controllably withdraw the gases, leaving the burning sections, through the ware once and then to reenter 10 into the upper part of the kiln and again be withdrawn in similar manner progressively throughout the length of the drying and heating sections of the kiln; and, to provide for such other objects, advantages and capabilities as will later appear and are inherently possessed by the invention.

Referring to the drawings, showing a preferred embodiment of the invention, Fig. 1 is a longitudinal vertical sectional view 20 through a kiln constructed in accordance with the invention; Fig. 2 is a longitudinal horizontal sectional view of the same; Fig. 3 is a vertical sectional view taken longitudinally through the hot medium duct and 25 the adjacent parts of the kiln; Fig. 4 is a transverse sectional view taken on line 4—4 of Fig. 1 at the entry end of the kiln; Fig. 5 is a transverse sectional view taken on line 5—5 of Fig. 1, and through the drying section of the kiln; Fig. 6 is a transverse sectional view taken on line 6—6 of Fig. 1 and through the pre-heating or heating section of the kiln; Fig. 7 is a transverse sectional view taken on line 7—7, and 30 through the burning or firing section of the kiln; Fig. 8 is a transverse sectional view taken on line 8—8, and through the sealing section of the kiln; and, Fig. 9 is a transverse sectional view taken on line 9—9, and 35 through the cooling section of the kiln.

Referring now more particularly to the drawings, the kiln illustrating the invention comprises a drying section 1, a heating or pre-heating section 2, a firing or burning section 3, a sealing section 4, and a cooling section 5, all arranged in longitudinal order to provide therethrough a ware passage 6 through which a train of cars 7, carrying the decks or stacks 8 of ware, may pass or 45 travel from the entry end 9 to the discharge end 10 of the kiln. Suitable gates or doors 11 and 12 may be provided respectively at the entry and discharging ends 9 and 10 of the kiln.

50 The cooling section 5 of the kiln comprises a lower passage part 13 and an upper extension 14 for providing therein a chamber or space 15 such that the space 15 may be in additional height at least equal to and preferably greater than the height of the passage 6 itself. Although, as shown in Fig. 1, this space is of substantially rectangular form, it is to be understood it might be inclined upwardly from the end 16 to the end 17 55 thereof without departing from the spirit

of the invention. At the upper end portion 17 is provided a suitable outlet passage or duct 18 for the exhaust or withdrawal of the hot or heated medium in the chamber 15, this medium having been heated by the 70 ware passing along the lower part of the cooling section in its cooling action. At the other end and in the lower part of the section 5, preferably at the sides of the passage 6 and opposite cross-ducts 19 provided in the car decks 8 are provided cold air ducts 20 and 21 through which the cold medium or cold air may be admitted into the lower part of the passage 6 near the discharge end thereof and of the section 5. 80 There is shown a plurality of these ducts, three in number as shown in Fig. 2 of the drawings, but it is to be understood that any desired number may be used, but they will be grouped more or less proximately 85 to the discharge end of the section 5. Each of these ducts are provided with valves 22 and 23 for regulating and controlling the admission of the cold medium into the passage 6 in the section 5.

In operation of this part of the kiln the cars 7 pass toward the discharge end of the section 5 and cold medium is admitted at the lower part of the passage 6 and into the cross-ducts 19. Inasmuch as the wares are placed in vertical position so that the air may pass vertically through the ware from the duct 19, it will be apparent that the cold air or cold medium will pass upwardly from the duct 19 through the ware and into the chamber 15. The first ascent of such medium will not have a great rise and probably will be at the height shown by the dotted line portion 24 shown in Fig. 1 of the drawings. The rise of this medium, which has been heated by the ware, will displace the hotter medium in the chamber 15 and cause the same to descend into further ware and hence through the same 95 into a cross-duct 19 and then laterally into the passage 6, where the medium will then proceed or progress in a direction opposite to the travel of the train and enter succeeding ducts 19 and pass upwardly through succeeding decks of wares and again rise into the chamber 15, this time at a greater height than previously and the process will continue in this manner with a greater rise 100 of the medium at each successive descent and ascent of the medium until it arrives at the end 17 of the chamber and then being of such a temperature that it no longer has any cooling characteristic and will then be withdrawn and exhausted through the duct 18 and used where desired, preferably in aiding in drying or heating the decks in the 105 drying and heating sections of the kiln.

In this way it will be apparent that the cooling is made more or less uniform and under control of the operator and in a cool- 110

ing section that is much shorter in length than have heretofore been required and at a greater rapidity than have heretofore been possible. The progress of the medium from 5 one end to the other end of the cooling section is uniform and efficient.

In order that this medium may not be wasted or lost by admission to other parts of the kiln, the latter is provided, at the rear of 10 the cooling section, with a sealing passage 26 of such a size in cross-sectional area as that the car and the deck will substantially fill this passage as the same pass through from the burning section to the cooling section. Fig. 8 shows a cross section of this 15 passage with a car and ware therein.

At the rear of the sealing section is provided a burning section, a detailed description of which will not be required here inasmuch as this part of the kiln already 20 forms part of another application and the operation and function of which will be readily understood by those skilled in the art.

25 At the rear of the burning section is located the heating or pre-heating section and a duct 27 which leads from the rear end of the burning section and extends the full length of the heating and drying section to 30 one side thereof and beneath the same as shown in Figs. 3, 4, 5 and 6 of the drawings. At intervals along the sides of the drying and heating sections are provided lateral ports 28 and 29 communicating with the 35 ware passages in said sections and leading into passages 30, 31, 32 and ducts 27 as clearly shown in Fig. 6 of the drawings. Each of the ports 28 and 29 is provided with a control or regulating damper or valve 33 40 so that the exhaust or withdrawal of the gases from the passage may be controlled or regulated as desired. The ports 28 and 29 are preferably located opposite the cross-ducts 19 of the car decks also as clearly 45 shown in Fig. 6 of the drawings.

Further to the rear of the section and above the same is provided or located a duct 34 having a blower or fan 35 having its exhaust pipe communicating with a vertical duct 36 which communicates at its lower end with the horizontal duct 27 as clearly shown in Fig. 3 of the drawings. The duct 34 communicates by a plurality of apertures or ports 37, 38, 39, 40 and 41 at intervals into 50 the upper part of the passage 6 into the heating and drying sections of the kiln as clearly shown in Fig. 1. The fan may be operated by any suitable means, as by an electric motor or the like, and it will be apparent from the above description that some of the heated gases passing in the duct 27 may be drawn therefrom through the duct 36 and discharged into the duct 34 for admission into the passage 6 through the ports 37, 55 38, 39, 40 and 41.

At the entry end of the kiln and connecting with the duct 27 is an exhaust duct 42 extending vertically and leading into the exhaust side of an exhauster or blower 43 having a discharge 44 for carrying off the exhausted media or the gases from the kiln, the exhauster being suitably operated by an electric motor 45 mounted upon the entry end of the kiln.

It will be noted from the above description 75 that the means for conducting the hot gases through the drying and burning sections is controlled at multiple points or stations for controlling and regulating the suction or withdrawal of the gases from the passage 80 of the sections and the cross-ducts of the decks and that these gases may pass upwardly into the duct 34 and be delivered into the upper part of the passage at the most efficient points so as to force these 85 gases downwardly through the car decks and ware for a vertical circulation therethrough and progressively toward the entry end of the kiln.

While we have herein described and upon the drawings shown a preferred form of the invention, it is to be understood that the invention is not limited to the particular details, constructions and arrangement of parts described and shown, but that it also comprehends other details, constructions and arrangements of parts without departing 90 from the spirit thereof.

Having thus described our invention, we 100 claim:

1. A kiln comprising a cooling section having a ware passage and a convection space above the passage.

2. A kiln comprising a cooling section having a ware passage and a chamber above 105 said passage and of a height at least equal to the height of the passage wherein the cooling medium may act in accordance with the laws of convection currents.

3. A kiln comprising a cooling section 110 having a ware passage extending upwardly a substantial distance to provide a chamber above said passage, and means for admitting cooling medium in the lower part of the passage.

4. A kiln comprising a cooling section having a ware passage extending upwardly a substantial distance to provide a chamber above said passage, means for admitting cooling medium in the lower part of the 115 passage, and means for regulating the admission of said medium into said passage.

5. A kiln comprising a cooling section having a ware passage extending upwardly a substantial distance to provide a chamber 120 above said passage, and means at the upper part of said chamber for conveying off the hot medium from the chamber.

6. In a tunnel kiln having a burning section and a cooling section, the cooling sec- 125

tion comprising a ware passage and an extension vertically of the passage and approximately of equal area to the passage, for affording free play of convection currents therein.

7. A kiln comprising a cooling section having a ware passage and an extension above the passage for convection currents, said extension rising progressively in a direction opposite to the movement of the ware.

8. A kiln comprising a cooling section having a short ware passage and a chamber of substantially the same length of the passage above the passage.

9. A kiln comprising a cooling section having a ware passage and a convection current chamber above the passage, means for admitting cold air at a lower part of the passage near one end thereof, and means for carrying off the hot gases at the upper part of the chamber at the other end thereof.

10. A kiln comprising a cooling section having a ware passage and a convection current chamber above the passage, and an air exit at the upper part of the chamber at an end thereof.

11. A kiln comprising a cooling section and a burning section, a sealing section between said burning and cooling sections.

12. A kiln comprising a cooling section and a burning section, a sealing section between said burning and cooling sections, and means above the cooling section for giving play for the currents of convection of the cooling section acting upon the ware in the cooling section, the sealing section substantially cutting off admission of the cooling medium into the burning section.

13. A kiln comprising a cooling section, means for vertically progressively cooling the ware passing through the section.

14. A method of cooling ware consisting in forcing cooling medium progressively in ascending and descending paths through the ware and into a convection space for free action of the convection currents in vertical relation to the ware.

15. A method of cooling ware consisting in forcing cooling medium progressively in ascending and descending paths through the ware and into a convection space for free action of the convection currents above the ware.

16. A method of cooling ware consisting in forcing cooling medium progressively in ascending and descending paths through the ware and into a convection space for free action of the convection currents above the ware, regulating the rate of admission of the cooling medium to the ware.

17. A method of cooling ware consisting in forcing cooling medium progressively in ascending and descending paths through

the ware, increasing the succeeding rise and fall of the medium as the same progresses along the ware in the cooling section of the kiln.

18. A method of cooling ware consisting in forcing cooling medium progressively in ascending and descending paths through the ware, increasing the succeeding rise and fall of the medium as the same progresses along the ware in the cooling section of the kiln, and regulating the rate of the rise and fall of the medium.

19. A kiln comprising heating and burning sections, a gas duct leading from the burning section and extending along the heating section, and bleeders for admitting and drawing the gases to and from the wares at intervals along the heating section.

20. A kiln comprising heating and burning sections, a gas duct leading from the burning section and extending along the heating section, and means for admitting the gases to an upper part of the heating section and for drawing the gases from the lower part of the section for causing a descent of the gases through the ware, said means acting to admit the gases to a further part of the heating section for progressive vertical circulation of the gases through the ware.

21. In a kiln, comprising a heating section, a single hot gas duct extending along the side and base of the section, multiple bleeders for controlling the withdrawal of the gases from the ware passage in the section, and means for conveying the withdrawn and hot gases to the upper part of the passage at progressive intervals for a thorough circulation of the gases in the ware.

22. A kiln comprising drying, heating and burning sections, a passage extending through said sections, a duct extending laterally of the drying and heating sections and connected to the burning section, a plurality of exhaust ports between the passage and the duct at intervals therealong, and means for drawing heating medium from said passage through said ports and into said ducts and conveying the medium to the upper part of said drying and heating sections for descending circulation of the medium in the ware in the passage.

23. A kiln comprising drying, heating and burning sections, a passage extending through said sections, a duct extending laterally of the drying and heating sections and connected to the burning section, a plurality of exhaust ports between the passage and the duct at intervals therealong, multiple means for regulating and controlling the passage of heating medium through said ports.

24. A kiln comprising drying, heating and

burning sections, a passage extending through said sections, a duct extending laterally of the drying and heating sections and connected to the burning section, a plurality of exhaust ports between the passage and the duct at intervals therealong, and means for drawing heating medium from said passage through said ports and into said ducts and conveying the medium to the upper part of said drying and heating sections for descending circulation of the medium in the ware in the passage, multiple means for regulating and controlling the

passage of heating medium through said ports. ¹⁵

25. A kiln comprising a cooling section and a burning section, a sealing section of reduced cross-sectional area and substantially the same in cross-sectional area of the material passing through the kiln, between said burning and cooling sections. ²⁰

In witness whereof, we hereunto subscribe our names to this specification.
